UNITED STATES PATENT OFFICE.

EDWARD ANDERSON, OF CHICAGO, ILLINOIS.

AUTOMATIC CRADLE-ROCKER.

SPECIFICATION forming part of Letters Patent No. 320,833, dated June 23, 1885.

Application filed May 21, 1884. (No model.)

To all whom it may concern:

Be it known that I, EDWARD ANDERSON, of Chicago, in the county of Cook and State of Illinois, have invented a new and Improved 5 Automatic Cradle-Rocker, of which the following is a full, clear, and exact description.

My invention consists in the construction and combination of parts, as will be herein-after fully described and claimed.

Reference is to be had to the accompanying drawings, forming a part of this specification, in which similar letters of reference indicate corresponding parts in all the figures.

Figure 1 is a transverse sectional elevation 15 of my improved automatic cradle-rocker, taken on the line $x-x$ of Fig. 2. Fig. 2 is a longitudinal section on the line $y-y$ of Fig. 1, and Fig. 3 is a transverse section on the line $z-z$ of Fig. 2.

1 make a supporting-frame for the rock-shaft a , by which the cradle b is to be suspended and rocked, consisting of a broad base-plate, c , with uprights d , a suitable distance apart for suspending the cradle between them, and a top plate, e , for staying the uprights at the top, and on one end of this supporting-frame I construct a case consisting of extensions of the base and top plates, end piece f , and sides g , in which I inclose a coiled 25 driving-spring, g , and a suitable multiplying and transmitting train of gear-wheels, 1 2 3, and pinions 4 5 6, connecting said spring with a crank-shaft, h , located in the upper part of the inclosing-case, the crank of which carries 30 a rod or pitman, i , working in a sleeve, j , on a crank, j' , of the rock-shaft, so arranged that the rotation of the crank-shaft h will cause a 35 rocking motion of the shaft a . The spring is to be arranged for being wound up by a key 40 applied to the winding-post k , as in other spring-power apparatus, and to drive by a pawl, l , and ratchet m ; and for regulating the speed I have provided a friction-brake, n , in 45 connection with the friction-disk o , fitted on the crank-shaft, with an adjusting-screw, p , extending down through the top of the case to work the brake.

To make an elastic contrivance of the brake for graduating the pressure I have connected 50 shoe n' by guide-pins q to a bar, u , to which the screw is connected with a number of coiled springs, s , between the shoe and the bar, said springs being fitted on suitable stays, t , thus contriving for such elasticity of the

brake as will avoid stopping the cradle too abruptly, or similarly releasing the spring-power, as would be the effect with the screw acting directly on the shoe n' .

To prevent a jerky motion to the cradle when the crank passes the centers, I propose 60 to hang the cradle-arms v loosely on the rock-shaft, and provide driving-arms w , rigidly secured to the shaft by set-screws x , and acting against springs y , fitted on a suitable stay-rod, z , extending from one to the other of the arms 65 of each end of the cradle and through the driving-arms, the springs forming buffers, which relieve the cradle of any shocks that might otherwise be imparted to it by the quick action of the crank in passing the cen- 70 ters.

In the top of the inclosing case for the driving mechanism I fit a door, a' , to afford access to the interior, and therein I arrange a box, b' , for a receptacle for such tools as may be required in the use of the machine.

Having thus described my invention, I claim as new and desire to secure by Letters Patent—

1. The automatic rocking-cradle herein described, consisting, essentially, in the supporting-frame, the driving mechanism in one end thereof, the rock-shaft a , operated from said mechanism, the cradle b , provided with arms v , loosely mounted on said shaft, and having the stay-rod z , connecting the arms at one end of 85 the cradle, springs y on said rod, and the driving-arms w , rigidly secured at their upper ends to the rock-shaft, and extending between the springs y on the rod z , substantially as set forth. 90

2. The combination, with the supporting-frame, the rock-shaft a , journaled therein, and the cradle b , suspended therefrom, of the spring-operating driving mechanism on said frame, the crank-shaft h , connected with the 95 rock-shaft, and a friction-disk, o , on said crank-shaft, the screw p , journaled in the frame, the curved bar u at the lower end of the screw, curved shoe n' below the bar u and adjacent to the friction-disk, the guide-pins q , 100 connecting the bar u and shoe n' , stays t , and spiral springs s , mounted thereon between the bar and shoe, substantially as set forth.

EDWARD ANDERSON.
